UNITED STATES PATENT OFFICE

PHILIP JAMES KENT, OF DETROIT, MICHIGAN, ASSIGNOR TO CHRYSLER CORPORATION, OF HIGHLAND PARK, MICHIGAN, A CORPORATION OF DELAWARE

IDENTIFICATION-PLATE FRAME

Application filed January 6, 1926. Serial No. 79,636.

It is the primary object of my invention to provide an ornamental frame surrounding an identification plate such as is used on automobiles, wherein the plate is locked to an instrument board or like object so as to prevent removal of the same from either side thereof. It is another object of my invention to lock the ornamental frame in the same general manner as the identification plate itself is locked.

With the above and other objects in view, my invention consists in the arrangement, combination and construction of the various parts of my improved device as described in the specification, claimed in my claims and shown in the accompanying drawing, in which:

Fig. 1 is a view in elevation showing an identification plate mounted on an automobile instrument board, portions of the board being broken away and a portion of the plate being broken away to illustrate its interior fastening.

Fig. 2 is a transverse sectional view of the same.

I have shown an instrument board 5 having a metal covering 6 thereon. An opening 7 is cut in the board 5 and a metal plate or bar 8 is inserted therethrough against the rearward side of the covering 6. Plugs 9 are inserted through openings in the covering 6 and screwed into aligned openings in the plate or bar 8 as at 10.

The covering 6 is countersunk as at 11 and an ornamental frame consisting of an exposed portion 12 and a countersunk portion 13 is provided with the countersunk portion 13 extending into the countersunk portion 11 of the cover 6. The plugs 9 are provided with flanges 14 which bear against the countersunk portion 13 of the frame, adjacent the holes 15 therein, when the plugs have been screwed home. It will be noted that slots 16 are provided in the top of the plugs 9 to receive a screw-driver or other like object and that when the plugs have been screwed home, the rearward end is beneath the surface of the bar 8.

The plugs 9 are provided with center apertures 17 in their forward ends as well as with

flanged forward ends 18. Inserts 19 are provided in the apertures 17, said inserts being tapered to a smaller diameter at their forward ends 20.

An identification plate 21 is inserted in the countersunk portion 13 of the frame and is provided with apertures adapted to closely engage around the forward ends of the plugs 9. The identification plate 21 is likewise provided, within its apertures, with rearwardly extending rings 22 which are forced between the flanges 18 on the forward ends of the plugs 9 and the tapered portions of the inserts 19 so as to securely lock the identification plate 21 in place.

It will be apparent that the identification plate 21 is securely locked against removal from its forward face and that the bar 8 or plugs 9 cannot be removed without defacing the instrument board or instrument board cover 6. It will further be apparent that the ornamental frame 12 is securely locked in place between the identification plate 21 and the instrument board cover 6 so as to prevent its removal without defacement.

I desire it to be understood that the term "instrument board", as used in the claims, is generic, to include either the board proper or its cover, or both, inasmuch as the opening 7 in the board 5 need not be made if the plugs 9 are extended through them.

It will be obvious that various changes may be made in the arrangement, combination and construction of the various parts of my improved device without departing from the spirit of my invention and it is my intention to cover by my claims such changes as may be reasonably included within the scope thereof.

What I claim is:

1. In combination, a support, a plate mounted on the support and having its edges forming a frame, an identification plate mounted over said first plate, within said frame portion, the side edges of the identification plate being covered by the frame and means consisting of plugs positioned between said identification plate and support having means thereon for securing both said plates against unauthorized removal.

2. In combination, a support, a countersunk plate mounted thereon, having its edges forming a frame, an identification plate mounted on said first plate, set within the countersunk portion, and means consisting of plugs positioned between said identification plate and support having means thereon for securing both said plates against unauthorized removal.
3. In combination, a support having a countersunk portion, a countersunk plate mounted with its countersunk portion in the countersunk portion of the support, an identification plate mounted in the countersunk portion of the first plate whereby the remainder of the first plate will act as a protecting frame for the side edges of the identification plate and means consisting of plugs positioned between said identification plate and support having means thereon for securing both said plates against unauthorized removal.
4. In combination, an instrument board for automobiles having openings therein, a plate mounted on said board having openings therein aligned with said first openings, plugs inserted through said openings having means thereon for securing said plate and board together, a border on said plate, forming a frame, an identification plate, within said frame, and means for securing the inside of said identification plate to said plugs, to prevent unauthorized removal of the frame or identification plate.
5. In combination, an instrument board for automobiles, having a countersunk portion, said portion having openings therein, an escutcheon plate fitted into said countersunk portion and formed with a marginal bead bearing against the face of the board surrounding said portion, said escutcheon plate having openings therein aligned with said first openings, a backing plate against the opposite face of the board, a pair of screw plugs, each plug comprising a shouldered head bearing against the escutcheon plate and a threaded shank inserted through the openings in the escutcheon plate and board, and screwed into said backing plate, and an identification plate seated on the escutcheon plate within the bead and covering the shouldered heads of the screw plugs, and means for anchoring said identification plate to said screw plugs.
